DESIGN FOR A TOILET POWDER CONTAINER

Elroy Kujawski, Jr., Adell, Wis.

Application April 2, 1948, Serial No. 145,499

Term of patent 3½ years

(Cl. D86—10)

To all whom it may concern:

Be it known that I, Elroy Kujawski, Jr., a citizen of the United States and resident of Adell, in the county of Sheboygan and State of Wisconsin, have invented a new, original, and ornamental Design for Toilet Powder Container, of which the following is a specification, reference being had to the accompanying drawing, forming part thereof.

Fig. 1 is a side elevational view of a toilet powder container showing my new design.

Fig. 2 is a top plan view of the same; and

Fig. 3 is a central longitudinal sectional view thereof.

I claim:

The ornamental design for a toilet powder container, as shown.

ELROY KUJAWSKI, JR.
